UNITED STATES PATENT OFFICE.

GEORGE PHILLIP WIEDMAN, OF NORTH TONAWANDA, NEW YORK.

DESIGN FOR AN AUTOMOBILE BODY.

Application filed October 6, 1925. Serial No. 15,035. Term of patent 14 years.

To all whom it may concern:

Be it known that I, GEORGE PHILLIP WIEDMAN, a citizen of the United States, and a resident of North Tonawanda, in the county of Niagara, State of New York, have invented a new, original, and ornamental Design for Automobile Bodies, of which the following is a specification, reference being had to the accompanying drawing, forming part thereof.

Figures 1 and 2 are perspective views, taken from opposite sides of an automobile body, showing my new design.

I claim:

The ornamental design for an automobile body as shown.

GEORGE PHILLIP WIEDMAN.
